ABSTRACT: A golf game comprising a flat flexible cellular playing surface having one or more holes (in a golf sense) at predetermined distances from a starting line with a flexible resilient stop bar permanently attached to the edges of the playing surface and each hole being provided with a flexible resilient retaining wall permanently attached to the playing surface at and along a portion of the lip edge of said hole furthest away from the starting line in such a manner so as to deflect a ball into the hole if driven with less than a predetermined amount of force but allowing the ball to continue on its course without deflection if the force so applied exceeds the predetermined amount of force.

GOLF GAME

This invention relates to a golf game and more particularly to a game for indoor or outdoor simulation of the usual game of golf.

BACKGROUND OF THE INVENTION

Heretofore it has been proposed to provide golf practice indoors by the use of single putting cups which could be placed on a carpet or rug. These cups provided no lasting challenge. Additionally the cups failed to simulate the conditions encountered on a golf course due to the conical approach surface about the cup.

Other devices attempting to simulate a golf course have been proposed. One device sought to simulate the flat playing surface required by the use of mechanical traps above the flat surface to hold the ball when it failed to stop at the designated spot. But this device provided no correlation by the user between the force applied to the ball and the result so obtained. Another device proposed a flat flexible surface with plastic or glass cups inserted into cylindrical sidewall openings to simulate golf holes. This approach proved to be unsatisfactory because the change of surface reduced the strip's flexibility and the golf ball would jump out or pop out of the hole due to its shallowness.

The present invention aims to overcome the foregoing objections and to provide an uniform putting course.

Another object of the invention is to provide a putting course of material having a cellular uniform surface upon which the ball will roll accurately and will provide a surface simulating a good putting green.

Yet another object of the invention is to provide a game apparatus which is flexible and will adapt itself to underlying surfaces and which may be rolled up or folded when not in use for convenient storage.

Still another object is to provide a game of amusement in which the player will not readily loose interest or be diverted by having only a fixed condition of play.

These and other objects will appear from the following description, reference being had to the accompanying drawings forming a part hereof.

SUMMARY OF THE INVENTION

In accordance with the foregoing objects there is provided a golf game comprising an elongated strip of flat flexible cellular sheet material of uniform and substantial thickness having a plurality of holes (in a golf sense) with cylindrically shaped sidewalls formed in and extending through the strip, the holes being spaced uniformly towards one end of the strip with a resilient stop bar permanently secured to and extending along at least substantially all of the edges of the strip and each hole being provided with a resilient stop bar permanently attached to the playing surface at and along a portion of the lip edge of the hole furthest away from the starting line in such a manner so as to deflect a ball into the hole if driven with less than a predetermined amount of force but allowing the ball to continue on its course without deflection if the force so applied exceeds the predetermined amount of force.

DESCRIPTION OF THE DRAWINGS

FIG. 1 is a plan view of the game apparatus;

FIG. 2 is a longitudinal cross-sectional view taken on line 4-4 of FIG. 1; and

FIG. 3 is a transverse cross-sectional view taken on line 3-3 of FIG. 1.

DETAILED DESCRIPTION

The invention generally comprises a game apparatus which includes an elongated strip of flexible material of uniform thickness which may be laid flat upon a floor or other support and having uniformly spaced holes towards one end of the

strip and stop bars of similar material provided along most of the edges of the strip to prevent overrunning of a ball.

Referring to the drawings which show one embodiment of the invention, the base of the game apparatus is an elongated strip 10 of flexible cellular or spongy material of uniform grain, the strip being of uniform thickness and having an exposed cellular surface adapted to engage the ball without slipping. A suitable strip 10 is made of foamed plastic such as urethane foam-polyester or other urethane foamed substances or foam-polyvinyl substances. Among the urethane foams the light density type of foam, e.g. about one to two pounds per cubic foot, are particularly preferred. The strip 10 is generally of about one-fourth to about one-half inch in thickness and about 3 to about 4 feet or more in width although wider strips 10 may be used where more holes are desired.

At one end of strip 10 two uniformly spaced starting lines 17, 18 are provided for positioning the ball prior to hitting it with a golf club.

Holes 13 are cut completely through strip 10 and uniformly spaced at intervals with respect to starting line 17 and at varying distances from the side of strip 10 so as not to be centered on the same longitudinal line. The hole size and shape is stabilized by stabilizing member 21 which is a fabric permanently secured to strip 10 along the bottom of hole 13. Preferably stabilizing member 21 is partially impregnated or coated with the plastic material of strip 10 to facilitate attachment.

Resilient stop bar 11 for stopping the roll of the ball is mounted across the ends of strip 10 and along the sides thereof. Optionally at the strip end by starting lines 17, 18 stop bar 11 may be omitted from one side for a short distance to facilitate obtaining the proper stance for hitting the ball while having maximum retention of the ball on the playing surface.

Each hole 13 is provided with a hole stop bar permanently attached to strip 10 at the lip edge of hole 13. The stop bar is mounted on that part of the lip edge of hole 13 which is away from starting line 17. Stop bar 15 is so positioned that a ball on a line of drive parallel to the strip 10 side edge and tangential to the lip edge of hole 13 will not touch stop bar 15. Said stop bar 15 extends substantially from about said tangential line on one side of hole 13 to about said tangential line on the other side of the hole. Stop bar 15 must be flexible enough to bend backward, i.e. away from starting line 17, to the playing surface of strip 10 when positioned along the hole lip edge. The minimum height of stop bar 15 being equal to about the radius of a standard golf ball minus the depth of hole 13 in strip 10. The flexible resilient stop bar 15 functions in such a manner so as to deflect a ball into hole 13 if the ball is driven with less than a predetermined amount of force but allows the ball to continue on its course if the force applied exceeds the predetermined amount, said amount being substantially the amount of force required to drive the ball from the starting line to the selected hole.

Stop bar 11, stop bar 15 and stabilizing member 21 may be secured to strip 10 by use of conventional adhesive or cement.

Further enjoyment of the game is provided by target circle 19, the outer edge of which is preferably about twice the size (or diameter) of hole 13.

Strip 10 may be printed or otherwise marked to designate the hole in terms of distance from starting lines 17, 18 and distance measuring means 23 with respect to the distance from starting lines 17, 18.

While other flexible materials may be used for strip 10 the urethane foam material has been found to have a coefficient of friction providing desired drag to the ball which makes it entirely satisfactory as a putting surface, the urethane strip may be mounted on the face of a flexible support such as sponge rubber if desired.

As illustrated in FIG. 1 strip 10 may be reduced in width at the end with starting lines 17, 18 if desired without reducing the enjoyment of the game or simulation of the usual game of golf.

While a certain embodiment and details have been described and illustrated in order to point out the invention, it

will be apparent to those skilled in the art that various modifications may be made therein without departing from the scope of the invention.

I claim:

1. In a golf game comprising an elongated strip of flat flexible cellular sheet material having (in a golf sense) a hole therein with cylindrically shaped walls the improvement which comprises attaching to the rearward portion of the lip edge of the hole with respect to the game starting point a flexible resilient stop bar permanently mounted to the strip whereby a golf ball if driven with less than a predetermined amount of force is deflected into the hole but allowing said ball to con-

tinue on its course without deflection if the force so applied exceeds said predetermined amount.

2. The golf game of claim 1 wherein a plurality of holes are uniformly spaced towards one end of said strip, a resilient stop

5 bar is permanently secured to and extends completely across each end of said strip and extends along substantially across the sides of said strip, two starting lines are uniformly spaced across the end of said strip furthest away from said holes and an accuracy target in the vicinity of said holes is provided.

10 3. The golf game of claim 2 wherein the strip is of a foamed urethane plastic.
